CLAIM

The ornamental design for a combined deodorant and perfume container, as shown and described.

DESCRIPTION

FIG. 1 is a top, front and left perspective view of a combined deodorant and perfume container showing our new design, the bottom, rear and right perspective view being the same; FIG. 2 is an exploded top, front and left perspective view thereof;

FIG. 3 is a front view shown without the end caps for a clear disclosure of the underlying parts. The rear view is a mirror image of the front view;

FIG. 4 is a top view thereof;

FIG. 5 is a right side view thereof;

FIG. 6 is a front view of another embodiment of the right side end cap shown in isolation, the rear view being a mirror image of the front view; and,

FIG. 7 is a right side view thereof.

The broken lines depict the end cap interior and portion of the right end that forms no part of the claimed design.
